(57) **CLAIM**

The ornamental design for a nightlight as shown and described.

DESCRIPTION

FIG. 1 is a perspective view of a nightlight;

FIG. 2 is a top plan view of the nightlight of FIG. 1;

FIG. 3 is a bottom plan view of the nightlight of FIG. 1;

FIG. 4 is a right side view of the nightlight of FIG. 1;

FIG. 5 is a left side view of the nightlight of FIG. 1;

FIG. 6 is a front view of the nightlight of FIG. 1; and,

FIG. 7 is a rear view of the nightlight of FIG. 1.

The broken lines in the drawings depict portions of the nightlight that form no part of the claim design.

1 Claim, 6 Drawing Sheets
